JOHANNES KRONE AND OTTO BEHNKE, OF ESSEN-ON-THE-RUHR, GERMANY
ASSIGNORS TO FRIED. KRUPP, OF ESSEN-ON-THE-RUHR, GERMANY.

GUN-CARRIAGE FOR PORTABLE GUNS.

SPECIFICATION forming part of Letters Patent No. 723,684, dated March 24, 1903.

Application filed December 29, 1902. Serial No. 137,009. (No model.)

To all whom it may concern:

Be it known that we, JOHANNES KRONE, residing at 56 Bismarckstrasse, and OTTO BEHNKE, residing at 36 Bismarckstrasse, Essen-on-the-Ruhr, Germany, subjects of the Emperor of Germany, have invented a certain new and useful Improvement in Gun-Carriages for Portable Guns, of which the following is a specification.

10 This invention relates to a gun-carriage for portable large-caliber guns with barrel recoil.

In moving portable guns of very large caliber from place to place it is ordinarily necessary to employ for that purpose a special transport-carriage, upon which the gun-barrel is placed by the assistance of lifting mechanism.

The present invention has for its object to enable the gun-barrel to be shifted in an easy and simple manner from the service-carriage to the transport-carriage without the assistance of special lifting mechanism. This object is attained, according to the present invention, by providing the transport-carriage with a slide-track corresponding with the slide-track of the cradle of the service-carriage and which can be so coupled with the slide-track of said cradle that it will constitute an extension of the same. In consequence of this arrangement the gun-barrel after it has been released from the recoil-brake and the recuperator of the gun can be drawn back upon the slide-track of the transport-carriage.

In the accompanying drawings one embodiment of the subject-matter of the present invention is illustrated by way of example, in which—

40 Figure 1 shows the transport-carriage in side elevation, the nearer wheels being removed and the relative position of the gun prior to the drawing back of the gun-barrel upon the transport-carriage being indicated by broken lines. Fig. 2 is a plan view of the transport-carriage, the position of the gun being indicated by broken lines. Fig. 3 is a section on the line 3-3, Fig. 1, looking from the right, the gun-barrel being uncoupled 45 from the recoil-brake and the recuperator and drawn back partly upon the slide-track

of the transport-carriage. Fig. 4 is a sectional detail view, the section being taken on the line 4-4, Fig. 1, looking from the left. Fig. 5 is a sectional detail view, the section 55 being taken on the line 5-5, Fig. 1, looking from the right. Fig. 6 shows schematically in side elevation the transport-carriage in connection with the service-carriage after the drawing back of the gun-barrel upon the slide-track of the transport-carriage; and Fig. 7 shows schematically in end elevation relative positions of the transport-carriage and the service-carriage due to an uneven position of the service-carriage wheels, the latter 60 being shown in broken lines.

The horizontal beam A of the transport-carriage is rigidly connected at one end with the axle b of the wheels B and engages at a point near its opposite end with the king-bolt 70 c of the car-truck C. The bolt c is so mounted upon the car-truck that it is offset a certain distance from the vertical plane of the axle c' of the car-truck, so that a lateral swinging motion will be imparted to the longitudinal beam 75 A in a horizontal plane by the swinging of the car-truck.

Mounted upon the axle b of the wheels B are two downwardly presented stops b' b', which, together with the lateral attachments 80 d d, which project outwardly from the gun-trail D, are designed to arrest the movement of the transport-carriage when the latter is moved up against the service-carriage to receive the gun-barrel.

85 Adjacent to the car-truck C on the longitudinal beam A is mounted a lifting device, which is designed to raise the gun-trail D. For this purpose, Fig. 4, a worm E is rotatably mounted in bearings a², projecting from the transverse wall a', extending between the longitudinal walls of the beam and also having a bearing in one of the longitudinal walls of said beam, which worm can be rotated through the medium of a crank e. Standing 90 in engagement with the worm E is a worm-wheel F, Figs. 1 and 2, likewise journaled on the transverse wall a', the vertical axis of which worm-wheel is connected, through a joint f, with a screw-spindle G. This screw-spindle G engages the female thread of a draw-rod H, which is provided on its free end

with an eye h and connected by a bolt with an eye d^2 on the tailpiece d' of the service-carriage. By turning the crank e in one direction or the other it is obvious that the screw-spindle G will be screwed onto or off of draw-rod H , so that the trail D will be raised or lowered. The joint f permits the lifting device to be folded up beneath the beam for transportation, where it may be held by any suitable means. (Not shown in the drawings.)

Upon two intermediate supports $J J'$, secured to the longitudinal beam A of the transport-carriage, is loosely mounted a barrel-holder K , the section of which corresponds, essentially, to that of the gun-barrel cradle on the service-carriage. The support J' is somewhat higher than the support J , so that the end of the barrel-holder adjacent to the car-truck C lies somewhat higher than the other end. The barrel-holder terminates at its end toward the car-truck C in an end wall k . Upon the upper edges of the lateral walls of the barrel-holder is mounted a slide-track k' , corresponding in form to the track on the cradle of the gun, which slide-track k' , in consequence of the described inclined position of the barrel-holder, drops somewhat toward the wheels B . The gun-barrel can be drawn backward upon this slide-track after it has been disconnected from the recoil-brake and the recuperator of the gun. In order to easily effect this drawing backward of the gun-barrel, there is provided a screw-spindle L , which is constructed to receive upon its hexagonal end l , toward the car-truck C , the similarly-formed hub of a bevel-wheel N . This screw-spindle may be turned in either direction through the medium of two cranks $m m'$ and corresponding bevel-gears $M M'$. In order to be able to engage the free end of the screw-spindle L with the nut o , formed in the horn O of the gun-barrel, the screw-spindle may be moved by hand in the hub of the wheel N a distance limited by the two shoulders $l' l''$. Adjacent to the intermediate support J is a spindle-support P , jointed to the under side of the barrel-holder K , so as to swing in a vertical plane into and out of position, and upon this support the screw-spindle L rests. At the time of drawing the gun-barrel back upon the transport-carriage this support may be laid down out of the way either by hand, through the medium of a hand-lever p , or automatically by impingement of the horn O of the gun-breach.

Located upon that end of the longitudinal beam A which lies toward the car-truck C is a ball-pivot bearing a^2 , in which a ball-pivot k^2 rests, and is held by a nut a^3 against lifting, and the barrel-holder may swing vertically and laterally from its transport position (shown in Figs. 1 and 2) in any desired direction about this ball-pivot k^2 .

In one of the side walls of the intermediate support J , Fig. 3, is mounted a hollow shaft Q , provided with a screw-thread and rotatable

but not movable longitudinally, rotation being imparted through the medium of a crank q . Engaging with the thread on this shaft Q is a draw-rod R , which terminates in an eye r , gripped between a pair of slotted guides k^3 , projecting downwardly from the under side of the barrel-holder K , while through the eye r and the slots of these guides k^3 a screw-bolt r' passes with play. A horizontal adjustment may be imparted to the barrel-holder K relatively to the longitudinal beam A by simply turning the crank q in the proper direction, the barrel-holder K swinging upon its ball-pivot k^2 , and by reason of the slotted guides k^3 the barrel-holder K may receive an upwardly-swinging movement or a tipping movement about its ball-pivot k^2 within limits defined by the length of the slots in said guides k^3 .

On opposite sides of that end of the barrel-holder lying distant from the car-truck C are angular feet S , Figs. 1 and 5, connected at their lower ends by a cross-bar s , which terminates on opposite sides in pins s' . Beyond the end of the barrel-holder K the feet S are extended and terminate in overlaps formed with eyes s^2 , adapted to be coupled by locking-bolts t each with one of the eyes T , formed on the under side of the rear end of the gun-cradle. On opposite sides of that end of the barrel-holder lying toward the car-truck C are feet U , braced by cross connection u , Fig. 4, and jointed to permit them to fold up for transportation, in which position they may be held by any suitable means. (Not shown.) The length of the feet S and U is fixed on the basis of the following hypothesis: Let it be supposed that the barrel-holder, together with the feet, is removed from the carriage and so connected to the gun-carriage that the feet rest in the rests d^3 and d^4 of the tail of the gun-carriage. The barrel-holder will then assume such a position that the gun-cradle can be brought by the elevating and traversing gear into a position in which the slide-track of the barrel-holder K forms a continuation of the slide-track of the gun-cradle. The two slide-tracks must in this case be inclined to the horizontal, so that when the tail of the gun-carriage is raised until the slide-tracks are horizontal the barrel-holder K will be approximately in the position as regards height which it assumes when it rests upon the transport-carriage.

The manipulation and operation of the gun-carriage are as follows: The transport-carriage is pushed as accurately as practicable, wheels B forward, over the midst of the carriage-trail D until the stops $b' b'$ abut against the projections $d d$ of the carriage-trail. The supports U and the parts $G H$ of the lifting device are then folded down into vertical position and the eye h of the draw-rod H is coupled with the eye d^2 of the gun-trail of the carriage by the insertion of a bolt. The trail is now raised by turning the crank e until the feet S come approximately into engagement

with their bearing-points d^3 upon the trail. If proper engagement of the feet S, as well as the feet U, with their bearing-points necessitates lateral movement of the barrel-holder

5 K with reference to the gun-trail, this is accomplished by turning the crank q of the horizontal swinging device or by swinging the car-truck. As soon as the feet S and U stand immediately above their bearing-points d^3 d^4 10 the carriage-trail is further raised. The feet S will first enter into engagement with their bearing-points d^3 in consequence of the relative lengths of the supports S and U. Since the service-carriage wheels, and consequently 15 the carriage-trail, will often lie in an inclined position relatively to the wheels of the transport-carriage in consequence of unevenness in the surface, one only of the feet S will at first engage with its bearing d^3 , and in consequence by further raising of the trail a lateral tipping of the barrel-holder K takes place about the ball-pivot k^2 until the other foot S has come into engagement with its bearing d^3 . If the trail is now still farther raised, the barrel-holder K swings upwardly with it, moving upon its ball-pivot k^2 . The feet U take part in the upward swinging of the barrel-holder K; but inasmuch as their rate of movement is very much less than the rate of upward 20 movement of their bearing-points d^4 the ends u' of the feet very quickly enter the bearing-points d^4 . As soon as this has taken place the barrel-holder is in the correct position and no further elevation of the trail takes 25 place. By the ordinary cranks of the elevating and horizontal training devices of the gun the gun-barrel or its cradle is now brought in such position that the slide-track k' of the barrel-holder K constitutes an extension of the 30 slide-track of the cradle. In this position the barrel-holder K is coupled with the gun-craddle by the insertion of the locking-bolts t into the eyes s^2 of the extensions on feet S and the eyes s^3 of the cradle. The gun-barrel is then 35 disconnected from the recoil-brake and the recuperator, and the screw-spindle L is moved axially by hand to a sufficient extent to cause it to engage with the internal thread o of the horn O on the gun-breech, when the crank m m' 40 is turned and the spindle L screws itself into the horn O until the shoulder l' abuts against the hub of the bevel-wheel N. From then on the turning of the spindle L causes the gun-barrel to slide from the track of the cradle 45 onto that of the barrel-holder K. When the horn O reaches the support P, the latter is thrown from beneath it and offers no hindrance to the further movement of the horn. The backward movement of the gun-barrel is 50 limited by the shoulder l' on the screw-spindle L. After releasing the coupling s² T the carriage-trail is again lowered to the ground by turning the crank e, by which operation the barrel-holder is again permitted to rest 55 upon the bearings J J', and the feet S and U are withdrawn from engagement with their bearings on the service-carriage. The lifting

device and the feet U are now folded and secured in their elevated position, whereupon the gun-barrel may be transported away upon 70 the transport-carriage.

The transfer of the gun-barrel from the slide-track of the transport-carriage upon the slide-track of the cradle takes place in a manner which is the reverse of that described 75 above.

The use of the ball-and-socket connections k^2 a^2 between the barrel-holder K and the transport-carriage is not indispensable, as any other suitable connection allowing the same or even greater freedom of the described movements of the barrel-holder, if desired, might be employed. Under some circumstances it might be desirable to omit this connection and in its place to use still another 80 arrangement to accomplish the horizontal movement of the barrel-holder—such, for instance, as a short chain or an arrangement like that for the intermediate bearing J—to wit, the parts q Q R r' k³. The screw-spindle L need not necessarily be arranged to have the short lost motion. It might be mounted to rotate in the barrel-holder without this longitudinal movement, in which case it would be desirable to employ for it, 85 for example, an accurately-guided nut upon the slide-track k' , with which the gun-barrel will be connected when it is to be run back upon the slide-track of the transport-carriage. In this last-named case the support 90 P and the thread o in the horn O can be done away with. A bore, however, would obviously be required in the horn on the gun-breech for the passage of the screw-spindle L.

Having thus described the invention, the 95 following is what is claimed as new therein:

1. A gun-carriage for large-caliber guns, comprising a service-carriage, and a transport-carriage provided with a slide-track constructed to receive the gun-barrel, and permit it to be slid from and to the service-carriage.

2. A gun-carriage for heavy-caliber guns with barrel-recoil, comprising a service-carriage constructed with a slide-track upon 115 which the gun-barrel recoils, and a transport-carriage also constructed with a slide-track, corresponding to the slide-track of the service-carriage, and constructed to be aligned therewith, whereby the gun-barrel may be 120 slid along its track on the service-carriage backward upon the track of the transport-carriage.

3. In a gun-carriage for large-caliber guns having barrel-recoil, the combination of a service-carriage having a cradle provided with a slide-track upon which the gun-barrel recoils, and a transport-carriage also provided with a slide-track, corresponding to the slide-track on the service-carriage, and constructed to be coupled end to end with the latter to form a continuation thereof and permit the gun-barrel to be slid along the tracks from one carriage to the other.

4. A gun-carriage for heavy-caliber guns with barrel-recoil, comprising a service-carriage constructed with a slide-track upon which the gun-barrel recoils, and a transport-carriage also constructed with a slide-track, corresponding to the slide-track of the service-carriage, and constructed to be alined therewith, and means for shifting one of the slide-tracks to aline it with the other, whereby the gun-barrel may be slid along its track on the service-carriage backward upon the track of the transport-carriage.
5. A gun-carriage for heavy-caliber guns with barrel-recoil, comprising a service-carriage constructed with a slide-track upon which the gun-barrel recoils, and a transport-carriage also constructed with a slide-track, corresponding to the slide-track of the service-carriage, and constructed to be alined therewith, means for connecting the tracks end to end, and means for shifting one of the slide-tracks to aline it with the other, whereby the gun-barrel may be slid along its track on the service-carriage backward upon the track of the transport-carriage.
6. A gun-carriage for heavy-caliber guns with barrel-recoil, comprising a service-carriage constructed with a slide-track, upon which the gun-barrel recoils, and a transport-carriage also constructed with a slide-track, corresponding to the slide-track of the service-carriage, and constructed to be alined therewith, means for imparting lateral movement to the track on the transport-carriage to bring it into alinement with the track on the service-carriage, whereby the gun-barrel may be slid along its track on the service-carriage backward upon the track of the transport-carriage.
7. In a gun-carriage for heavy-caliber guns with barrel-recoil, the combination of a service-carriage having a slide-track upon which the gun-barrel recoils, a transport-carriage also provided with a slide-track, means for holding the slide-tracks together, and means for imparting vertical movement to the slide-track on the transport-carriage to bring it into position to form a continuation of the track on the service-carriage.
8. In a gun-carriage for heavy-caliber guns with barrel-recoil, the combination of a service-carriage having a slide-track upon which the barrel recoils, and a transport-carriage having a slide-track mounted thereon with vertical, horizontal and tilting movements, whereby it may be moved into alinement with the track on the service-carriage, when the respective carriages are standing on uneven surfaces.
9. In a gun-carriage, the combination of the service-carriage having a recoil slide-track, and a trail, a transport-carriage having a slide-track, vertically movable thereon, means on the transport-carriage for lifting the service-carriage trail, and feet through which the trail raises the slide-track on the transport-carriage, proportioned to establish the proper position of the latter relatively to the service-carriage to permit alinement of the two tracks.
10. In combination with a service-carriage having a trail a transport-carriage having a slide-track mounted to tilt and to move vertically, lifting connections for the trail, and lifting-feet on opposite sides of the slide-track through which the trail raises and tilts the slide-track for the purpose set forth.
11. In a gun-carriage for large-caliber guns having barrel-recoil, the combination of a service-carriage having a cradle provided with a slide-track upon which the gun-barrel recoils, and a transport-carriage also provided with a slide-track, corresponding to the slide-track on the service-carriage and constructed to be coupled end to end with the latter to form a continuation thereof and permit the gun-barrel to be slid along the tracks from one carriage to the other, with a screw-spindle mounted rotatably on the transport-carriage beneath and longitudinally of the slide-track of the latter, and means for connecting said screw-spindle to the gun-barrel, for the purpose of shifting the latter from the slide-track of the service-carriage on the slide-track of the transport-carriage and vice versa, by turning the screw-spindle.
12. In a gun-carriage for heavy-caliber guns with barrel-recoil, the combination of a service-carriage, constructed with a slide-track upon which the gun-barrel recoils, and a transport-carriage also constructed with a slide-track, corresponding to the slide-track of the service-carriage, and constructed to be alined therewith, with stops on either carriage for defining and limiting the relative movements of the service-carriage and transport-carriage.
13. A transport-carriage for large-caliber guns, provided with a slide-track constructed to receive the gun-barrel and to permit it to be slid on said track to and from the service-carriage.
14. A transport-carriage for heavy-caliber guns, which are mounted with barrel-recoil when in service, said transport-carriage being constructed with a slide-track adapted to be alined with the slide-track of the service-carriage for the purpose set forth.
15. A transport-carriage by which to transport the barrel of a large-caliber gun, provided with a slide-track constructed to be coupled end to end with the service-carriage of the gun, and to receive the gun-barrel from the latter.
16. A transport-carriage upon which to transfer the barrel of a heavy-caliber recoil gun, provided with a slide-track upon which the gun may be slid, from its service-carriage, said slide-track being constructed to aline with the service-carriage and having means for shifting it to bring it into such alinement.
17. A transport gun-carriage constructed with a slide-track upon which the gun-barrel may be slid from its service-carriage, having means for connecting its slide-track with the

service-carriage, and shifting said slide-track to bring it into alinement therewith.

18. A transport gun-carriage constructed with a slide-track upon which the gun-barrel 5 may be slid from its service-carriage, and means for imparting vertical and horizontal movement to said slide-track to bring it into alinement, for the purpose set forth.

19. A transport gun-carriage upon which to 10 mount the barrel of a heavy-caliber recoil-guns in transporting from place to place; said carriage being constructed with a slide-track upon which the barrel is slid to and from the carriage, and means for imparting transverse 15 and tilting movements to said cradle to bring it into proper position to receive the gun-barrel.

20. A transport gun-carriage for the barrels of heavy-caliber recoil-guns consisting of a suitable carriage, a slide-track mounted

upon said carriage, and a screw extending longitudinally of said carriage, provided with means for turning it and adapted to engage the gun to move it on the track. 20

21. In a transport gun-carriage, the combination of the slide-track, mounted upon said carriage, with transverse movement, a screw for transversely adjusting the slide-track on the carriage, and a flexible connection between said screw and the slide-track to permit said track to move angularly. 25

The foregoing specification signed at Dusseldorf this 12th day of December, 1902. 30

JOHANNES KRONE,
OTTO BEHNKE.
